UNITED STATES PATENT OFFICE.

HENRY ALCOCK, OF COBRIDGE, COUNTY OF STAFFORD, ENGLAND.

DESIGN FOR A VEGETABLE-DISH.

SPECIFICATION forming part of Design No. 14,640, dated February 12, 1884.

Application filed December 13, 1883. Term of patent 7 years.

To all whom it may concern:

Be it known that I, HENRY ALCOCK, of Cobridge, England, have invented and produced a new and original Design for a Vegetable-Dish, of which the following specification is a full, clear, and exact description, reference being had to the accompanying drawing, forming part of this specification.

The drawing represents a perspective view of the newly-designed vegetable-dish.

This invention relates to a new configuration for a vegetable-dish or other china household article—such as a tureen, sugar-dish, pitcher, or sauce-boat.

It consists of a dish, A, made of oblong form, the two opposite sides being parallel, or nearly

so, and joined by beveled corners. Each side is composed of a brim or upper section, a, which is concave, a central straight section, b, a lower inwardly-projecting section, c, and a foot, d.

e is one of the handles.

The dish may be ornamented in suitable manner and color.

I claim as my design—

The design for a vegetable-dish, having brim a, straight section b, inwardly-projecting section c, and foot d, as described and shown.

HENRY ALCOCK.
